Primary Examiner—Ruth McInroy(74) Attorney, Agent, or Firm—McCarthy Tétrault LLP; Christopher N. Hunter(57) CLAIM

The ornamental design for barbecue condiment rack, as shown.

DESCRIPTION

FIG. 1 is an isometric view of a barbecue condiment rack showing the new design;

FIG. 2 is a front view of the barbecue condiment rack of FIG. 1;

FIG. 3 is a top view of the barbecue condiment rack of FIG. 1; and,

FIG. 4 is an end view of the barbecue condiment rack of FIG. 1.

The design is shown in solid lines in the drawings. The broken lines are for illustrative purposes only and form no part of the claimed design.
